(57) CLAIM

The ornamental design for a memorial flag display case, as shown and described.

DESCRIPTION

FIG. 1 is a perspective view showing my new design;

FIG. 2 is a front elevation view thereof;

FIG. 3 is a left side elevation view thereof;

FIG. 4 is a right side elevation view thereof;

FIG. 5 is a back elevation view thereof; and,

FIG. 6 is a top plan view thereof.

The bottom of the display case is plain and unornamented.

The broken lines shown in FIG. 1 are for illustrative purposes only and form no part of the claimed design.
